UNITED STATES PATENT OFFICE.

ABRAHAM L. KENDRICK, OF SOUTH NORWALK, AND WILLIAM J. WILEY,
OF DANBURY, CONNECTICUT, ASSIGNORS OF ONE-THIRD TO HARRY
MCLACHLAN, OF DANBURY, CONNECTICUT.

NON-REFILLABLE BOTTLE.

SPECIFICATION forming part of Letters Patent No. 662,945, dated December 4, 1900.

Application filed January 22, 1900. Serial No. 2,366. (No model.)

To all whom it may concern:

Be it known that we, ABRAHAM L. KENDRICK, residing at South Norwalk, and WILLIAM J. WILEY, residing at Danbury, Fairfield county, Connecticut, citizens of the United States, have invented certain new and useful Improvements in Non-Refillable Bottles; and we do hereby declare the following to be a full, clear, and exact description of the invention, such as will enable others skilled in the art to which it appertains to make and use the same.

Our invention relates to certain improvements in non-refillable bottles, and has for its object to provide a bottle into which after the contents have been introduced the cork may be readily inserted, while such cork cannot be thereafter removed without detection.

In the accompanying drawings, which form a part of this application, Figure 1 is a broken elevation of our improvement; Fig. 2, a broken sectional elevation of the same; Fig. 3, a plan of the top of the bottle, and Fig. 4 is a perspective view of the cap or hood.

Similar numbers of reference denote like parts in the several figures of the drawings.

1 is any suitable bottle whose neck is surmounted by a hood 2, closed at the top and sides and open at the ends. The distance between the sides is equal to the inside diameter of the neck of the bottle, while on the inside of such neck, near the bottom thereof, is formed a shoulder or ledge 3.

4 is a perforation in the top of the hood. The cork 5 is introduced and pushed within the hood from one side thereof until such cork is immediately above the mouth of the bottle, and then any suitable rod or other de-

vice is introduced through the perforation 4 and driven against the cork to force the latter down into the neck of the bottle against this shoulder or ledge 3, as shown at Fig. 2.

The hood and bottle are of course made of fragile material, and it will be clear that the cork cannot be removed until the hood is first broken, and therefore it will be clear that the cork cannot be removed without ready detection.

Having thus described our invention, what we claim as new, and desire to secure by Letters Patent, is—

1. A non-refillable bottle whose mouth is surmounted by a perforated hood closed at the top and sides and open at the ends, substantially as set forth.

2. A non-refillable bottle provided with a shoulder on the inside of its neck and having its mouth surmounted by a perforated hood closed at the top and sides and open at the ends, whereby the cork may be introduced through one of said ends and depressed against said shoulder by a suitable tool introduced through the perforated hood, substantially as set forth.

In testimony whereof we affix our signatures each in the presence of two witnesses.

ABRAHAM L. KENDRICK.

WILLIAM J. WILEY.
